UNITED STATES PATENT OFFICE.

CARROLL KNOWLES, OF CRANSTON, AND HUBERT D. TANNER, OF PROVIDENCE, RHODE ISLAND, ASSIGNEES TO BROWN AND SHARPE MANUFACTURING COMPANY, OF PROVIDENCE, RHODE ISLAND, A CORPORATION OF RHODE ISLAND.

GRINDING-MACHINE

1,324,124.

Specification of Letters Patent. Patented Dec. 9, 1919.

Application filed May 8, 1918. Serial No. 233,235.

To all whom it may concern:

Be it known that we, CARROLL KNOWLES and HUBERT D. TANNER, citizens of the United States, residing at Cranston and Providence, respectively, both in the county of Providence and State of Rhode Island, have invented certain new and useful Improvements in Grinding-Machines; and we do hereby declare the following to be a full, clear, and exact description of the invention, such as will enable others skilled in the art to which it appertains to make and use the same.

The invention relates to grinding machines which are adapted for grinding cylindrical or tapered work, and more particularly to the means for supporting and driving the grinding wheel of machines of this type.

The grinding wheels of universal machines of the above type are usually supported upon a head which is carried upon a wheel slide, and may be adjusted either angularly or both angularly and longitudinally with relation thereto, the slide being mounted to move longitudinally upon a swivel base, which is adjustably mounted on the machine frame. It is one object of the present invention to provide a novel belt drive for the grinding wheel of such a machine which will enable the wheel to be driven from a pulley mounted in the machine frame, and preferably at one side and somewhat below the wheel head, and which will automatically maintain a substantially uniform tension on the belt during all movements and adjustments of the wheel head. To this end the forward and return runs of the driving belt are passed over guide pulleys arranged to permit the adjustments and movements of the wheel head, and one or more of which are so connected with the wheel head that the requisite motion is transmitted to such pulley or pulleys from the head to maintain the normal belt tension whenever the head is moved in making any of the adjustments for which the machine is adapted, or in effecting the cross feed of the grinding wheel slide. This insures the proper action of the belt without requiring special adjustment or manipulation of the belt guiding pulleys, and without the use of spring or weight-operated takeup pulleys. The belt guiding pulleys are prefer-

ably arranged to lead the belt laterally over the wheel head, since such arrangement contributes to a simple and compact construction of the head supporting parts and the head slide operating mechanism, and also permits the driving pulley to be conveniently located in the machine base.

A further object of the invention is to simplify the construction of the parts for supporting the wheel head and securing it in adjusted position on the slide. To this end means are provided for securing the wheel head directly upon the slide which will permit the adjustment of the head both angularly and longitudinally. This eliminates the platen on which the head has been adjustably mounted in prior machines having the same range of adjustment. The means for thus securing the wheel head on the slide preferably consists of a ring surrounding a circular base on the head, and adjustably secured on the slide, by clamping devices which clamp both the ring and the wheel head to the wheel slide.

The features of the invention will be readily understood from an inspection of the accompanying drawings and the following detailed description of the mechanism illustrated therein.

In the drawings, Figure 1 is a sectional side elevation showing so much of a grinding machine as is necessary to illustrate the application of the present invention thereto; Fig. 2 is a plan view of the parts shown in Fig. 1; Fig. 3 is a rear elevation showing the wheel driving mechanism; Fig. 4 is a detail in elevation, looking toward the left in Fig. 3; and Fig. 5 is a sectional detail on line 5—5, Fig. 2.

The machine shown in the drawings is provided with a reciprocating work table 2, a swivel table 4 mounted thereon and provided with ways 6 on which the head-stock and tail-stock are adjustably mounted, these parts being constructed and operated in any usual manner.

The grinding wheel 8 is secured on the end of a grinding wheel shaft 10 which is mounted in suitable bearings carried by the grinding wheel head 12. The head is provided with a cylindrical base 14 which rests upon the upper surface of the grinding wheel slide 16 and is secured in position on the slide by three clamping devices which

embrace the base and are longitudinally adjustable on the slide. As shown, each clamping device comprises a disk 18 arranged to overlie the projecting flange of the base, and a bolt 20, the head of which is arranged to engage one or the other of two T-slots 22 and 24 which extend longitudinally of the wheel slide. The cylindrical base enables the head to be angularly adjusted within the clamping disks, and the T-slots enable the head to be adjusted longitudinally of the slide. The clamping devices and cylindrical base are maintained in proper relation to each other during the adjustments of the wheel head by a ring plate 26 which fits about the cylindrical base of the head and rests upon the upper surface of the wheel slide. The clamping bolts 20 pass through holes in the ring, and the clamping disks 18 rest upon the heads of bearing screws 28 which project above the surface of the ring and are substantially in the plane of the flange on the wheel head which is engaged by the disks. This construction is simple and compact, and enables the wheel head to be readily and conveniently adjusted either angularly or longitudinally upon the wheel slide and to be quickly and securely clamped in adjusted position.

The wheel slide is mounted to move longitudinally on ways formed on the wheel slide base 29, and is actuated by the pinion 31 secured to the upper end of a shaft 33 and engaging a rack on the slide. The shaft 33 is operated through cross feed mechanism which may be of any usual construction. The wheel slide base 29 is mounted for angular adjustment upon the machine frame, and is held in adjusted position by clamping bolts 35, the heads of which engage an angular T-slot 37 formed in the base.

The grinding wheel shaft is driven through a belt 30 which passes over a pulley 32 on the shaft and over a driving pulley 34 which is mounted in the machine frame, and is preferably located at one side and below the grinding wheel head, as shown. The forward and return runs of the belt pass over guide pulleys which are so mounted and arranged with relation to the driving and wheel shaft pulleys that they permit the adjustments and feeding movements of the wheel head, and some or all of which are relatively moved during such adjustments or movements to automatically maintain the belt tension. These guide pulleys are also preferably arranged to lead the belt to and from the wheel shaft pulley laterally over the wheel head. In the preferred construction shown, the driving pulley is an elongated pulley or drum along which the belt may move as occasion requires, and the forward run of the belt passes from the driving pulley up over a guide pulley 36, the

axis of which is at an angle to the axis of the driving pulley so that it changes the plane and direction of travel of the belt. From the guide pulley 36 the belt extends in a substantially horizontal direction laterally over the wheel head to a vertical guide pulley 38 which is mounted on the wheel head, and which again changes the plane and direction of travel of the belt. From the guide pulley 38 the belt passes over the horizontal driving wheel pulley, and thence to a vertical guide pulley 40 mounted on the head directly below the pulley 38, which acts like the pulley 38 to change the plane and direction of the return run of the belt. From the pulley 40 the belt passes in a substantially horizontal direction laterally over the wheel head to a guide pulley 42 arranged above the driving pulley 34, with its axis at an angle to the axis of the driving pulley, so that the plane and direction of travel of the belt is changed and the belt is directed down about the driving pulley.

The guide pulleys 36 and 42 are mounted in the pulley brackets 44 and 46, which are pivotally supported in vertical bearings 48 and 50 in a support 52 so that the pulleys may swing to accommodate themselves to variations in the direction of travel of the belt passing over them. The support 52 in which the pulley brackets are mounted is arranged to move longitudinally of the pulley 34 to compensate for variations in the positions of the guide pulleys 38 and 40 and the wheel shaft pulley 32 incident to adjustments or movements of the wheel head. As shown, the support is carried upon the upper end of a swinging lever 54 to which the support is pivotally connected by a shaft 56 secured in lugs 58 at the upper end of the lever, and engaging bearing lugs 60 on the support.

To automatically maintain the belt tension during the movements or adjustments of the wheel head, the support for the guide pulleys 36 and 42 is so connected with the head that the requisite movement is imparted to the pulleys from the head whenever the head is moved or adjusted. Means is also preferably provided for positively maintaining the guide pulley 42 for the return run of the belt in proper alignment with the belt leading from the pulley 40 on the wheel head. As shown, the means for accomplishing these results comprises a rack 120 bar 62 connected with the pulley support 52 and pulley bracket 46, and engaged by a segment 64 secured to the wheel head and having its pitch surface substantially in line with the surfaces of the guide pulleys 38 and 40. As indicated in Figs. 1 and 2, the segment 64 is formed on an arm projecting from the bracket 66 which supports the upper end of the vertical shaft 68 on which the pulleys 39 and 40 are mounted. The rack 120

bar is supported in a bearing bracket 70 having arms embracing the segment 64 and adapted to turn on the shaft 68. The rear end of the rack bar is connected by a pivot 5 with a clevis 72 formed on the forward end of a rod 74 which is held in the end of a sleeve 76 by a screw 78, the inner end of which engages an annular groove in the rod. The sleeve 76 forms one section of a telescoping shaft, the other section of which consists of a rod 80 fitting within the sleeve and having its rear end secured to the pulley bracket 46. By means of the rod 80, sleeve 76 and rack bar 62, the guide pulley 42 is 10 maintained in alinement with the belt leading from the pulley 40, whatever the position of the wheel head.

The connections between the rack bar 62 and the pulley support 52 comprises a 20 sleeve 82 which is connected to the sleeve 76 by a pivot bolt 84, and is connected with the pulley support 52 by a rod 86. The rear end of the rod is connected with the pulley support by a pivot bolt 88, and the forward end of the rod fits within the sleeve 82 and is connected therewith by an adjusting screw 90. A hand wheel 92 is secured on the forward end of the adjusting screw so that the screw may be conveniently turned 30 to adjust the distance between the guide pulleys 36 and 42 and the pulleys 38 and 40 on the wheel head, and thus secure the proper belt tension.

Through the connections described the 35 guide pulleys 36 and 42 will be positively moved by movement of the wheel head to maintain the belt tension. The connections between the rack bar 62 and the pulley support 52 are so arranged and proportioned 40 that the movements imparted to the guide pulleys 36 and 42 when the wheel head is moved or adjusted will compensate for the movement of the guide pulleys 38 and 40, and will also compensate for the variation 45 in the wrap of the belt about the pulleys 38 and 40 incident to such adjustment or movement.

While it is preferred to employ the specific 50 construction and arrangement of parts shown and described, particularly in embodying the invention in a universal grinding machine similar to that illustrated in the drawings, it will be understood that this construction and arrangement is not essential to the broader features of the invention, and may be varied and modified as found 55 desirable or best suited to the construction and arrangement of the parts in the machine in which it is to be embodied.

Having explained the nature and object of 60 the invention, and specifically described one form of mechanism in which it may be embodied, what is claimed is:

1. A grinding machine, having, in com- 65 bination, a grinding wheel head, a wheel

shaft having a pulley thereon mounted in the head, a longitudinally movable wheel slide on which the head is angularly adjustable, a driving pulley mounted in the machine frame, a driving belt passing over 70 the driving and wheel shaft pulleys, guide pulleys for the forward and return runs of the belt arranged to permit the adjustment and movement of the grinding wheel head, and connections for moving one or more of 75 said guide pulleys from the head to automatically maintain the belt tension whenever the head is moved or adjusted.

2. A grinding machine, having, in combination, a grinding wheel head, a wheel 80 shaft having a pulley thereon mounted in the head, a longitudinally movable wheel slide on which the head is angularly adjustable, a driving pulley mounted to rotate on a fixed axis in the machine frame, 85 a driving belt passing over the driving and wheel shaft pulleys, guide pulleys for the belt arranged to direct the forward and return runs laterally over the head, and means for automatically causing a relative move- 90 ment of the pulleys to maintain the belt tension whenever the head is moved or adjusted.

3. A grinding machine, having, in combination, a grinding wheel head, a wheel 95 shaft having a pulley thereon mounted on the head, a wheel slide on which the head is angularly adjustable, a base on which the wheel slide is longitudinally movable, a frame on which the base is angularly ad- 100 justable, a driving pulley mounted in the frame, a driving belt passing over the driv- ing and grinding wheel pulleys and a plurality of guiding pulleys arranged to direct the belt laterally over the head, and means 105 for automatically operating one or more of the pulleys to properly guide the belt and to maintain the belt tension whenever the head is moved or adjusted.

4. A grinding machine, having, in com- 110 bination, a grinding wheel head, a wheel shaft having a pulley thereon mounted in the head, a longitudinally movable wheel slide on which the head is angularly adjustable, a driving pulley mounted in the ma- 115 chine frame, a driving belt passing over the driving and wheel shaft pulleys, two guide pulleys on the head back of the wheel shaft pulley each arranged to change the plane and the direction of travel of the belt, two 120 guide pulleys at one side of the head over which the belt passes from the pulleys on the head to the driving pulley, and connec- 125 tions between the latter two guide pulleys and the head through which the pulleys are moved to maintain the belt tension whenever the head is moved or adjusted.

5. A grinding machine, having, in com- 130 bination, a grinding wheel head, a wheel shaft having a pulley thereon mounted in

- the head, a longitudinally movable wheel slide on which the head is angularly adjustable, a driving pulley mounted in the machine frame, a driving belt passing over the 5 driving and wheel shaft pulleys, two guide pulleys on the head the axes of which are normal to the axis of the wheel shaft, and two guide pulleys mounted for movement longitudinally of the driving pulley and 10 connected to be moved by the head to maintain the belt tension whenever the head is moved or adjusted.
6. A grinding machine, having, in combination, a grinding wheel head, a wheel shaft having a pulley thereon mounted in the 15 head, a longitudinally movable wheel slide on which the head is angularly adjustable, a driving pulley mounted in the machine frame, a driving belt passing over the 20 driving and wheel shaft pulleys, two guide pulleys at one side of the head arranged with their axes at varying angles to the axis of the driving pulley to change the plane and direction of travel of the belt leading from 25 the driving pulley over said pulleys, two guide pulleys at the rear of the wheel shaft over which the belt leads in a substantially horizontal direction from the former guide pulleys and arranged with their axes sub- 30 stantially normal to the axis of the wheel shaft pulley to change the plane and direction of travel of the belt, and means for automatically changing the relative positions of the pulleys to maintain the belt tension whenever the head is moved or ad- 35 justed.
7. A grinding machine, having, in combination, a grinding wheel head, a wheel shaft having a pulley thereon mounted in the 40 head, a longitudinally movable wheel slide on which the head is angularly adjustable, a driving pulley mounted in the machine frame, a driving belt passing over the driving and wheel shaft pulleys, two guide 45 pulleys on the head with their axes substantially normal to the axis of the wheel shaft, a segment having its pitch surface substantially coincident with the surfaces of the pulleys, a rack bar engaged by the segment, 50 and guide pulleys connected with the rack bar over which the belt passes from the pulleys on the head to the driving pulley.
8. A grinding machine, having, in combination, a grinding wheel head, a wheel shaft 55 having a pulley thereon mounted in the head, a longitudinally movable wheel slide on which the head is angularly adjustable, a driving pulley mounted in the machine frame, a driving belt passing over the driving and wheel shaft pulleys, two guide 60 pulleys on the head the axes of which are substantially normal to the axis of the wheel shaft, two guide pulleys over which the belt
- passes from the pulleys on the head to the driving pulley, a support movable longitudinally of the driving pulley on which the latter guide pulleys are pivotally supported, and a connection between the head and one of said pulleys for maintaining said pulley in alignment with the belt passing over it. 65
9. A grinding machine, having, in combination, a grinding wheel head, a wheel shaft having a pulley thereon mounted in the head, a longitudinally movable wheel slide on which the head is angularly adjustable, a 70 driving pulley mounted in the machine frame, a driving belt passing over the driving and wheel shaft pulleys, two guide pulleys on the head the axes of which are substantially normal to the axis of the wheel 75 shaft, two guide pulleys over which the belt passes from the pulleys on the head to the driving pulley, a support for said pulleys movable longitudinally of the driving pulley, a rack bar connected to said support, 80 and a segment secured to the head engaging said rack bar.
10. A grinding machine, having, in combination, a grinding wheel head, a wheel shaft having a pulley thereon mounted in the head, a longitudinally movable wheel slide on which the head is angularly adjustable, a driving pulley mounted in the machine frame, a driving belt passing over the 85 driving and wheel shaft pulleys, two guide pulleys on the head, guide pulleys over which the belt passes from said pulleys to the driving pulley, and means for relatively moving the guide pulleys from the head to compensate for the movement of the guide pulleys on the head and for the variation in the 90 wrap of the belt about said pulleys. 100
11. A grinding machine, having, in combination, a wheel slide, a grinding-wheel head having a cylindrical base resting on the slide, a grinding wheel shaft in the head, and clamping devices overlying the base and adjustable longitudinally of the slide. 105
12. A grinding machine, having, in combination, a wheel slide, a grinding-wheel head having a cylindrical base resting on the slide, a grinding wheel shaft in the head, a ring plate surrounding the base and adjustable longitudinally of the slide, and clamping devices for clamping the ring and base in adjusted positions. 110
13. A grinding machine, having, in combination, a wheel slide, a grinding-wheel head having a cylindrical base resting on the slide, T-slots extending longitudinally of the slide, a ring plate surrounding the base, clamp disks overlying the base and ring, and clamping bolts passing through the 115 disks and ring and engaging the T-slots. 120
